United States Patent Office

Des. 216,301

Patented Dec. 16, 1969

216,301

ENDLESS FLEXIBLE TRACK UNIT

Guy-Noel Chaumont, Princeville, Quebec, Canada
(34 La France, Victoriaville, Quebec, Canada)

Filed Feb. 26, 1969, Ser. No. 15,921

Term of patent 14 years

Int. Cl. D12—14

U.S. Cl. D14—24

FIG. 1

FIG. 2

FIGURE 1 is a top perspective view of an endless flexible track unit showing my new design; and

FIGURE 2 is a top plan view of a section of the endless flexible track unit shown in FIGURE 1.

I claim:

The ornamental design for an endless flexible track unit, as shown.
